Primary Examiner — Mark A Goodwin(57) **CLAIM**

The ornamental design for a solar universal bracket, as shown and described.

DESCRIPTION

FIG. 1 is a first perspective view of a solar universal bracket showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the solar universal bracket thereof; and,

FIG. 10 is an enlarged view of the selected portion in FIG. 1.

The broken lines shown in the drawings depict portions of the solar universal bracket in which the design is embodied that form no part of the claimed design.
